COLLAPSIBLE INFANT'S CRIB AND PLAYPEN

Andrew Keck, Worthington, Ohio

Application June 17, 1950, Serial No. 168,722

2 Claims. (Cl. 5—98)

1

The present invention relates to collapsible baby cribs, and more particularly to an improved portable and collapsible combined infant's crib and play pen.

The principal object of the present invention is to provide a collapsible infant's crib which may be folded into a relatively compact package for transportation, and which, after folding, may be easily erected or assembled into a rigid crib-forming configuration.

Another object of the present invention is to provide a combined infant's crib and play pen which may be utilized by campers or travelers, and which preferably is formed from wood or metallic frame members which function to support a fabric body covering which lends itself to facile folding and compact storage.

It is another object of this invention to provide in an infant's crib a collapsible frame structure which, when moved to its crib-forming shape, functions to tension an associated fabric covering to hold the same in a taut condition.

For a further and more detailed understanding of the present invention and the various additional objects and advantages realized therefrom, reference is made to the following description and the appended drawings, wherein:

Fig. 1 is a perspective view of my improved collapsible infant's crib and play pen showing the same in its erected position;

Fig. 2 is a side elevational view of the supporting frame of the crib shown in Fig. 1;

Fig. 3 is a detailed vertical sectional view taken along the line 3—3 of Fig. 2;

Fig. 4 is a similar view along the line 4—4 of Fig. 2;

Fig. 5 is a fragmentary top plan view looking down upon an upper corner of the crib;

Fig. 6 is an end elevational view of the supporting frame showing the outer fabric covering in broken lines;

Fig. 7 is a horizontal sectional view taken along the line 7—7 of Fig. 6;

Fig. 8 is a top plan view of one of the side sections of the supporting frame occupying its folded or collapsed position;

Fig. 9 is a fragmentary top plan view taken through one corner of a modified supporting frame construction formed in accordance with the present invention;

Fig. 10 is a fragmentary end elevational view of the modified frame shown in Fig. 9;

Fig. 11 is an exploded perspective view of one corner of the modified construction shown in Fig. 9;

2

Fig. 12 is an exploded perspective view taken through a corner of still another modification of the supporting frame of the present collapsible infant's crib and play pen.

Fig. 13 is a top plan view of the modification shown in Fig. 12; and

Fig. 14 is a vertical sectional view taken along the line 14—14 of Fig. 13.

Referring now to the drawings, and particularly to Fig. 1 thereof, it will be seen that the present invention makes use of a collapsible supporting frame, generally designated by the numeral 15, which comprises a pair of spaced side-forming sections each having a horizontal longitudinal member 16 to which is pivotally connected, as at 17, a pair of upright corner posts 18. The frame members 16 and 18 are preferably formed from suitable wood or light metallic stock, and the longitudinal base members 16 are provided a distance inwardly of their respective ends with openings 19 for the reception of pivot bolts 20 which extend through the horizontal base members 16 and the upright corner posts 18 to provide for pivotal swinging movement of the corner posts between upright positions, as shown in Fig. 1, and horizontally folded positions, as shown in Fig. 8.

As shown particularly in Fig. 4 of the drawings, the longitudinal base members 16 are formed toward their outer ends with dowel-receiving sockets 21 which receive dowel extensions 22 formed on the ends of a pair of spaced detachable transverse base frame members 23. The longitudinal base members 16 and the transverse base members 23 form a substantially rectangular base frame, while the corner posts 18 extend upwardly from the base frame for the support of an upper rectangular frame, to be hereinafter more fully described.

The corner posts 18 are formed at their upper ends with upwardly opening slots 24 for the reception of outwardly extending screw-threaded bolts 25 which project diagonally outwardly from the ends of a pair of transversely disposed upper frame members 26. The outermost ends of the bolts 25 extend through openings formed at either end of a pair of longitudinal frame members 27 and receive cooperatively threaded wing nuts 28. The transverse upper frame members 26 and the longitudinal members 27 define an upper rectangular frame whose area is slightly less than the area defined by the rectangular base frame due to the slightly inwardly inclined disposition of the corner posts 18. As shown in Figs. 1 and 6, a fabric covering 29 is adapted to

be supported upon the frame 15, and is formed with a bottom panel 30, side panels 31, and end panels 32. The outer marginal edges of the separate panels of the covering are folded backwardly and stitched along seams 33 to provide a plurality of edge channels to receive the transverse and longitudinal upper frame members.

To assemble and erect the present infant's crib and play pen shown in Fig. 1, assuming the separate parts of the frame and covering to be disassembled, the transverse and longitudinal upper frame members, 26 and 27 respectively, are inserted through the pocketed channels formed in the outer marginal edges of the side and end panels 31 and 32 of the outer covering 29. The ends of the respective transverse and longitudinal upper frame members are then loosely connected, as by means of the bolts and wing nuts 25 and 28. The covering is then spread outwardly to arrange the bottom wall 30 thereof in a substantially horizontal plane. The longitudinal members 16 of the lower frame, together with the corner posts 18, with the latter occupying their folded positions, are inserted through the lower corner openings of the outer covering to occupy positions upon the inside of the outer covering in the approximate location as shown in Fig. 1. Thereafter, the corner posts at one end of the crib are swung upwardly to a substantially vertical position and the intermediate portions of the bolts 25 are inserted within the open slots 25 formed on one set of corner posts 18. The opposite end corner posts 18 are then swung upwardly to positions to receive the bolts 25 carried at the opposite end of the crib. In this position, the outer covering 29 is loosely supported on the lower and upper frame members. The transverse lower frame members 23 are then positioned between the end regions of the longitudinal lower frame members 16 and on the inner side of the end panels 32 of the outer covering. To finally tension the outer covering about the frame members, the person assembling the crib places a foot upon the longitudinal lower frame members 16 at one corner of the crib and pulls upwardly upon the longitudinal upper frame members 27 at the corner to tension the corner regions of the outer covering. While holding the frame in its tensioned condition, the wing nuts 28 are separately tightened upon the bolts 25 to securely clamp the transverse and longitudinal upper frame members to the upper portions of the corner posts 18. As shown particularly in Fig. 3 of the drawings, the upper ends of the posts 18 are beveled in order to prevent downward sliding movement of the upper frame members 26 and 27 after initial tightening of the wing nuts 28. In this manner, the outer covering may be tensioned initially upon tightening of the nuts 28 and thereafter will remain in a taut condition.

When it is desired to disassemble the combined crib and play pen for purposes of storage or transportation, the wing nuts 28 are initially loosened upon the bolts 25, and thereafter the transverse members 23 of the lower frame are disconnected from the longitudinal members 16 and the bolts 25 at one end of the crib withdrawn from the slots 24 formed in the corner posts. The corner posts 18 are then folded into parallelism with the members 16. Thereafter, the transverse upper frame members 26 may be detached from the longitudinal upper frame members 27 and withdrawn from the marginal edge channels of the covering. The transverse frame members 23 and 26 may thereafter be loosely positioned ad-

jacent the longitudinal frame members and the entire assembly rolled into a compact cylindrical shape for storage or transportation.

Referring now to Figs. 9-11, there is disclosed a modified upper corner construction for the present collapsible infant's crib and play pen, wherein a tubular corner post 18a, having a generally rectangular cross-sectional configuration, is formed to receive an upper corner-forming member 19a which is formed with perpendicularly related extensions 20a and 21a for insertion within tubular transverse upper frame members 26a and longitudinal upper frame members 27a. The shank portion of the upper corner-forming member 19a is provided upon its outer side surfaces with a serrated region 22a cooperative with a spring latch or pawl 23a which is carried upon the outer side of the tubular corner post 18a. The serrated region 22a of the member 19a is arranged to provide a plurality of transversely extending ratchet teeth into which the end of the pawl 23a may enter to lock the corner-forming member 19a against downward movement within the corner post 18a, while at the same time providing for upward lifting of the corner-forming member with respect to the post 18a.

In operation, the corner structure disclosed in Figs. 9-11 may be initially assembled by inserting the shank of the corner-forming member 19a to its full depth within the post 18a. This is accomplished by pulling outwardly upon the pawl 23a to free the same from the ratchet teeth 22a. Thereafter, the transverse and longitudinal upper frame members 26a and 27a may be inserted through the marginal edge channels of the outer covering of the crib, and then inserted over the perpendicularly related extensions 20a and 21a, at which time the corner regions may be lifted upwardly upon posts 18a to tension the outer covering upon the entire frame of the crib.

Referring to the additional modification disclosed in Figs. 12-14, it will be seen that the upper corner regions of the crib comprise the corner posts 18b which possess a substantially rectangular tubular cross-sectional configuration, and which are formed a distance inwardly from the upper ends thereof with longitudinally extending slots 35. Slidably carried within the upper end of each of the posts 18b is a rectangular block member 36 which is provided with relatively narrow side projections 37 and 38, and centrally with a substantially vertically disposed screw-threaded bore 39. The extension 37 is arranged to enter the tubular transverse upper frame member 26b, and is provided with a hemispherical projection 40 which fits within a circular opening 41 formed a distance inwardly from the ends of the transverse upper frame member 26b. As shown particularly in Fig. 14, the hemispherical projection 40 serves to lock the transverse upper frame members 26b against accidental disengagement from the block 36. The opposite extension 38 of the block is adapted to enter a slot 42 formed in the side wall of the tubular longitudinal upper frame member 27b, and the extension 38 is provided with a recessed region 43 adjacent to the body of the block 36 into which the upper portion of the side wall of the tubular member 27b may enter upon insertion of the extension 38 through the slot 42. A rectangular end cap 44 is provided to close the upper end of the post 18b, and is formed with a circular bore 45 in which the reduced shank portion 46 of a screw crank 47 is rotatably carried.

The threaded shank region of the crank 47 extends through the threaded bore 39 of the block 36, and, as shown in Fig. 14, serves to elevate or depress the sliding block 36 and the upper frame members 26b and 27b with respect to the post 18b. The slots 35 formed in the side walls of the post 18b provide for the outward projection of the extensions 37 and 38.

In operation, the assembly shown in Figs. 12-14 provides for the initial depression of the slidable block 36 within the post member 18b prior to attachment of the upper frame members 26b and 27b to the extensions 37 and 38. After the upper frame members 26b and 27b are inserted through the marginal edge channels of the outer covering of the crib, the ends thereof are engaged with the extensions 37 and 38 of the sliding blocks 36, whereupon the cranks 47 are rotated in directions to elevate the blocks 36 and the upper frame members with respect to the corner posts 18b, whereby to stretch the outer covering of the crib about the base frame thereof.

In view of the foregoing, it will be seen that the present invention provides an efficient portable and collapsible infant's crib and play pen which is characterized by an extremely rigid and rugged construction when occupying an erected position. By providing for sliding adjustment of the upper frame with respect to the corner posts of the crib, the outer fabric covering may be drawn to a tight, resilient condition about the supporting frame, and may be held in such taut condition against sagging by nature of the upper corner constructions set forth. Further, combined cribs and play pens formed in accordance with the present invention may be assembled and disassembled with facility through the simple bolt and wing nut connections disposed at the upper corner portions of the crib. Thereafter, the corner posts may be folded into flat parallel relation to the longitudinal base frame members which may thereafter be rolled into the outer covering to provide a neat and compact package which lends itself to ready portability and transportation.

While certain specific forms of the invention have been disclosed in detail, it will be understood that various modifications with respect to construction details may be accomplished without departing from the spirit of the invention or the scope of the following claims.

I claim:

1. A collapsible infant's crib comprising a supporting frame including a pair of spaced parallel lower side members, detachable lower end members, corner post members carried substantially at the ends of said lower side members for pivotal swinging movement between substantially folded

positions in parallel relation to said lower side members and erected positions in substantially perpendicular relation to said lower side members, a pair of longitudinally disposed spaced parallel upper side members, and a pair of spaced parallel transverse upper end members; means detachably connecting said upper side and end members with the upper end portions of said corner posts, said last-named means providing for relative vertical movement of said upper side and end members with respect to said corner posts; and an outer covering carried at its marginal edges by said upper side and end members and surrounding said lower side and end members.

2. A collapsible infant's crib comprising a substantially rectangular lower frame section including a pair of spaced parallel side members and a pair of spaced parallel end members detachably carried at the ends of said side members; a plurality of corner-forming post members pivotally carried by the side members of said lower frame section for swinging movement between folded positions in substantially parallel relation to the side members and upright positions in substantially perpendicular relation to the side members; a substantially rectangular upper frame section including detachably united spaced parallel side and end members; means detachably connecting said upper frame section with the upper portions of said corner-forming posts, said last-named means providing for vertical adjustment of said upper frame section with respect to said lower frame section; and a flexible outer covering including bottom, side, and end panels extending between the side and end members of said lower and upper frame sections and around said corner-forming posts, the side and end panels of said outer covering being formed along their upper edges with pockets to receive the side and end members of said upper frame sections and being arranged to be stretched taut by vertical adjustment of said upper frame section with respect to said lower frame section.

ANDREW KECK.
